(57) **CLAIM**

The ornamental design for a gun sight, as shown and described.

DESCRIPTION

FIG. 1 is a front, upper, right perspective view of a gun sight of our new design;

FIG. 2 is a rear, upper, left perspective view thereof;

FIG. 3 is a rear, bottom, left perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and

FIG. 9 is a bottom view thereof.

FIG. 10 is a front, upper, right perspective view of another embodiment of a gun sight of our new design;

FIG. 11 is a rear, upper, left perspective view thereof;

FIG. 12 is a rear, bottom, left perspective view thereof;

FIG. 13 is a front view thereof;

FIG. 14 is a rear view thereof;

FIG. 15 is a left view thereof;

FIG. 16 is a right view thereof;

FIG. 17 is a top view thereof; and,

FIG. 18 is a bottom view thereof.

Broken lines of equal length (e.g., dash-dash) represent portions of the gun sight and form no part of the claimed design.

1 Claim, 18 Drawing Sheets
